UNITED STATES PATENT OFFICE.

STEPHEN FAITH AND SAMUEL KLASSTORNER, OF CHICAGO, ILLINOIS, ASSIGNEES TO FAITH MFG. CO., OF CHICAGO, ILLINOIS, A CORPORATION OF ILLINOIS.

DESIGN FOR A RADIATOR-CAP ORNAMENT.

Application filed October 18, 1927. Serial No. 23,785. Term of patent 7 years.

To all whom it may concern:

Be it known that we, STEPHEN FAITH and SAMUEL KLASSTORNER, citizens of the United States, residing at Chicago, Illinois, have invented a new, original, and ornamental Design for Radiator-Cap Ornaments, of which the following is a specification, reference being had to the accompanying drawing, forming part thereof.

The figure is a side elevation of a radiator cap ornament showing our new design.

We claim:

The ornamental design for a radiator cap ornament as shown.

STEPHEN FAITH.
SAMUEL KLASSTORNER.
